EXTERNALLY FIRED PERFORATING GUN

Philip W. Martin, Huntington Park, Calif.

Application October 29, 1945, Serial No. 625,177

12 Claims: (Cl. 164—0.5)

1

This invention relates to well perforating guns whereby projectiles are shot through the wall of casing set in a well to provide communication of the interior of the casing with the surrounding formation.

Guns of this character have been successfully and extensively employed. However, certain difficulties have been encountered in the use of these guns, one difficulty resulting from the necessarily short gun barrel length. In view of the shortness of the gun barrel, the propelling effect of the expanding gases from the burning of the powder charge in these guns is limited to that short space of time which it takes for the projectile to travel through the barrel. For the purpose of obtaining a greater utilization of the potential projectile-propelling capacity of the powder charge employed in these guns, many expedients have been adopted, among which are shear rings on the projectiles and plates or flanges at the rear ends of the projectiles, to restrain the projectiles from movement until the pressure of combustion products from the burning of the powder against the rear ends of the projectiles builds up to an effective value. These expedients have accomplished higher projectile velocities and therefore greater penetrating ability of the projectiles but from tests and observations, I have determined that an efficient use of the powder is not obtained in these guns and that too large a portion of the powder is expelled from the gun barrels in unburned state and therefore without useful effect.

It is an object of my present invention to greatly increase the projectile-propelling efficiency of the powder charge in perforating guns, as compared to that which is obtained in the most efficient guns of this character now employed. By use of the invention I am able to obtain from a given powder charge an increase of approximately 100% in the penetrating capacity of the projectile, as the result of a great increase in velocity, or the same penetration by the projectile with only approximately one-half the previously required powder charge. For example, in the practice of my invention, with seventy grains of powder I have produced greater penetration than is obtained by the use of one hundred and thirty grains of powder in the old type of gun having a shear plate at the rear end of the projectile.

It is an object of the invention to provide in a perforating gun of the character described a propelling charge comprising a mass of powder grains and an effective quantity of gaseous medium (including air) in the propelling charge chamber, at least a portion of which gaseous medium occupies the spaces existing between the powder grains of the powder mass, and to provide a simple and effective means for exploding

the powder charge by compression of the entire content of the propelling charge chamber which lies behind the projectile at the rear end of the gun barrel. It is an object of the invention, hereinafter described in detail as an example only, to provide a projectile firing arrangement wherein a firing charge of powder is placed in the outer part of the gun barrel adjacent the front end of the projectile and the outer end of the gun barrel is closed by a wall which prevents the compression of the firing and propelling charges by hydrostatic pressure encountered in the well, and means are provided for igniting the firing charge so that the pressure developed thereby will drive the projectile rearwardly in the gun barrel against the contents of the propelling charge chamber, which contents include the powder charge and the gaseous elements residing in the propelling charge chamber, and which gaseous elements are distributed throughout the small spaces existing between the powder grains of the propelling charge. The interspersed gaseous elements of the propelling charge are thereby compressed in an instantaneous manner, causing a rapid rise in the temperature throughout the entire propelling charge to or above the ignition point of the powder grains of the propelling charge. This causes all of the powder grains, or a very large proportion thereof, to start burning simultaneously and to immediately produce a high propelling pressure, without detonation or such excessive pressure as to cause swelling of the gun body, against the rear face of the projectile to initiate its outward movement. A further object of the invention is to provide in the propelling charge a powder grain size which is determined with relation to the length of time it takes the projectile to travel through the gun barrel, so that the individual powder grains will have a burning time sufficiently long to produce a continued generation of gas to maintain pressure throughout the outward movement of the projectile through the relatively short gun barrel so that a high velocity thereof is developed. A further contribution to the efficiency of the perforating gun is the closer approach to complete burning of the powder grains, without detonation or rapid burning which approaches close to detonation, by the time the projectile leaves the gun barrel.

It is a further object of the invention to provide a simple and effective means for firing the gun and for preventing application of pressure to powder charges in a gun of the character described, resulting from the lowering of the gun deep into the fluid in a well in which the perforating operation is to be conducted. Accordingly, the desired ignition and burning characteristics of the powder charges are maintained, the result being that the operating characteris-

tics of the gun are maintained substantially constant, regardlessly of the different hydrostatic pressures to which the gun is subjected in the well.

A further object of the invention is to provide a perforating gun having the general characteristics referred to in the foregoing, wherein the loading operations are simplified and the manner of firing the propelling charges is simple and effective.

An object of the invention is to provide a perforating gun having a body with a plurality of gun bores, the inner end of each gun bore having therein a loosely dispersed firing charge containing a gas space or spaces, and means for preventing external pressure from compressing the powder charge when the gun is lowered into a well, such means consisting of a thin shell which entirely covers the outer ends of the bores and is maintained in sealing relation to the body.

It is a further object of the invention to provide a perforating gun wherein the propelling charges are exploded by compression resulting from inward movement of the projectile, this gun having a shell disposed around the gun body in such relation as to provide a space communicating with the outer ends of the gun barrels, and means for producing a fluid pressure in this space to drive the projectile rearward to compress the propelling charges. It is a further object to provide a gun of the character set forth in the preceding paragraph, wherein the pressure in the space between the body and the shell is produced by explosion of a firing charge in a chamber which communicates with the space.

Further objects and advantages of the invention will be brought out in the following part of the specification.

Referring to the drawing which is for illustrative purposes only,

Fig. 1 is a partly sectioned view of one embodiment of the perforating gun.

Fig. 2 is an enlarged fragmentary section taken as indicated by the line 2-2 of Fig. 1.

Fig. 3 is an enlarged fragmentary section showing an alternative means for producing pressure at the outer ends of the gun bores.

Fig. 4 is also a fragmentary section showing another means for producing pressure at the outer ends of the gun bores.

The perforating gun shown in Fig. 1 includes a metal body 10 having at its upper end a cable connection 11 by which an electric cable 12 is connected to the body 10, this cable 12 having an insulated conductor 13 extended therethrough for connection with the firing means 14 which is situated at the lower end of the internal body 15 of the cable connection 11. In the body 10, at the lower end of the internal body 15 of the cable connection 11, there is a firing charge chamber 16, communicating with the exterior of the gun body through a passage 17.

The gun body 10 has a plurality of radial gun bores 18 which may be disposed along a spiral path. Around the exterior of the gun body 12 I place a shell or cover 19 which extends over and covers the outer ends of the gun bores 18. The shell 19 is disposed in sealing relation to the body 10. To accomplish this disposition of the shell 19, I have provided at the upper end of the body 10 an annular projection 20, which may be undercut so as to receive a packing ring 21 which is pressurally engaged by the upper end of the shell 19. On the lower end of the body 10 there is a cap 22 having a counterbored cylindric wall 23 which

overlaps the lower end of the shell 19 and provides a space to receive an annular packing member 24. A nut 25 threaded onto a screw 26 which projects downwardly from the body is employed to apply upward pressure against the cap 22 so that the packing member 24 will be compressed and the shell 19 will be forced upwardly so as to compress the packing ring 21.

The body 10 and the shell 19 are so formed and disposed with relation to each other as to provide an intervening space 27 connecting the passage 17 with the outer end of all of the gun bores 18. This space 27, in the embodiment of the invention disclosed, consists of a helical channel 15 in the outer face of the body 10, such channel 27 communicating at its upper end with the passage 17 and having intermediate portions thereof connecting the outer ends of the gun bores 18, the lower end of the channel 27 ending at and communicating with the lowermost of the gun bores 18.

Prior to the placing of the shell 19 on the body 10 each of the gun bores 18 is loaded as shown in Fig. 2. In the inner end of the bore 18 I place 25 a propelling charge 30, such propelling charge 30 occupying a space which may be referred to as the propelling charge space or chamber 31 communicating with the inner end of the gun bore 18. A projectile 32 is then placed in the gun bore 18 so that it will occupy a position between the propelling charge 30 and the outer end of the bore 18. The shell 19 is then placed on the body 10 in the manner shown in Fig. 1, this shell 19 then sealing the outer ends of the gun bores 18. When the gun is to be lowered into a well, a firing charge of powder 33 is then placed in the firing charge chamber 16, and the cable connection 11 is installed. The firing means 14 may consist of any of the known types of electrically ignited fuses. I have shown the firing means 14 as consisting of an electrically fired cartridge 35 disposed in a block 36 which is threaded into the lower end of the body 15 of the cable connection 11, the block 36 holding the cartridge 35 in such position that it will operatively engage the electrical contact 37 which is connected to the conductor 13 of the cable 12.

When the gun is lowered into the well by means of the cable 12 and enters the fluid content of the well, the hydrostatic pressure of the well is prevented from acting upon the projectiles to force the same rearwardly so as to compress the propelling charges 30; therefore, the propelling charges 30 are maintained at relatively low pressure. These propelling charges 30 are placed in the spaces 31 at atmospheric pressure, and, during the lowering of the gun into the well, the only increase in pressure against the propelling charges 30 is that which may result from increase in temperature encountered in the well fluid. The propelling charge 30 comprises powder grains which may be of any form and are generally either flat or annular. They are so disposed with relation to each other that the mass of powder of the propelling charge 30 is of cellular structure, that is to say, adjacent substantially each and every one of the grains there is a small gas space. Also, there may be a gas filled space externally of the mass of powder grains.

Firing of the gun is accomplished by electrically igniting the priming cartridge 35 which in turn ignites the firing charge 33. The combustion products from the burning of the firing charge 33 pass through the passage 17 and then through

the space or channel 27 to the outer ends of the gun bores 18, the pressure of these combustion products driving the projectiles rearward so as to quickly compress the contents of the propelling charge space 31. The compression of the gas content of the propelling charge results in high temperature generation in contact with the surfaces of substantially all of the powder grains so that the powder grains all start burning at the same time to produce a propelling gas to drive the projectiles 32 out through the gun bores 18 and through the shell 19 at high velocity.

In Fig. 3 I indicate a form of the invention wherein a small fuse 40 is extended through a helical channel 27' in the gun body 10, this channel 27' traversing the outer ends of the gun bores

18. The upper end of the fuse 40 may be extended through the passage 17 into the firing charge chamber 33 where it will be ignited by the primer 35. In the outer ends of the gun barrels, as indicated in Fig. 3, a firing charge 42 is placed, which is ignited by the fuse 40, the pressure generated by the ignition of the charge 42 driving the projectile 32 rearwardly to compress the contents of the propelling charge chamber, to ignite the same in the manner hereinbefore described. As shown in Fig. 4, a firing charge 44 may be placed in the outer end of each bore 18 for ignition by a flame which passes through the channel 27 from the firing charge chamber 16 when a heat and/or flame producing charge of powder is burned in the chamber 16. The force exerted against the projectiles 32 by the burning of the firing charge 44 will drive the projectiles 32 rearwardly to compress the contents of the propelling charge chambers 31, thereby igniting the propelling charges 30 therein.

As explained hereinbefore, the discharged projectiles penetrate the shell 19 and then they pass through the casing into the formation. When the gun, after its use, is withdrawn from the well, the gun bores or barrels 18 are reloaded and a new shell 19, consisting simply of a length of steel tubing, is substituted for the perforated shell 19.

I claim as my invention:

1. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a shell around said body in sealed relation thereto, said body and said shell being so relatively formed as to provide a space between them communicating with the outer ends of all of said bores; a propelling charge in each of said propelling charge chambers; projectiles in said bores adapted to be driven rearwardly so as to compress the contents of said propelling charge chambers; and means for communicating a pressure through said space into the outer ends of said bores to drive said projectiles rearwardly whereby the contents of said propelling charge chambers will be compressed and said propelling charges ignited to discharge said projectiles from said bores and through said shell.

2. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with

the rear end of each bore; a shell around said body in sealed relation thereto, said body and said shell being so relatively formed as to provide a space between them communicating with the outer ends of all of said bores; a propelling charge in each of said propelling charge chambers; projectiles in said bores adapted to be driven rearwardly so as to compress the contents of said propelling charge chambers; and means for communicating an explosive blast through said space into the outer ends of said bores to drive said projectiles rearwardly whereby the contents of said propelling charge chambers will be compressed and said propelling charges ignited to discharge said projectiles from said bores and through said shell.

3. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a shell around said body in sealed relation thereto, said body and said shell being so relatively formed as to provide a space between them communicating with the outer ends of all of said bores; a propelling charge in each of said propelling charge chambers; projectiles in said bores adapted to be driven rearwardly so as to compress the contents of said propelling charge chambers; a firing charge in the outer end of each bore; and means for transmitting a firing effect through said space to said firing charges thereby exploding said firing charges so as to drive said projectiles rearwardly, whereby the contents of said propelling charges will be compressed and said propelling charges ignited to discharge said projectiles from said bores and through said shell.

4. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a shell around said body in sealed relation thereto, said body and said shell being so relatively formed as to provide a space between them communicating with the outer ends of all of said bores; a propelling charge in each of said propelling charge chambers; projectiles in said bores adapted to be driven rearwardly so as to compress the contents of said propelling charge chambers; a firing charge in the outer end of each of said bores; and means for transmitting an ignition effect through said space to ignite said firing charges and thereby build up pressure in the outer ends of said bores to drive said projectiles rearwardly, whereby the contents of said propelling charge chambers will be compressed and said propelling charges ignited to discharge said projectiles from said bores and through said shell.

5. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a thin walled cover member on said body covering the outer ends of all of said bores, said body and said cover member being so relatively formed as to provide

a space communicating with the outer ends of said bores; a propelling charge in each of said propelling charge chambers; projectiles in said bores adapted to be driven rearwardly so as to compress the contents of said propelling charge chambers; and means for communicating a pressure through said space into the outer ends of said bores to drive said projectiles rearwardly, whereby the contents of said propelling charge chambers will be compressed and said propelling charges ignited to discharge said projectiles from said bores and through said shell.

6. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a thin walled cover member on said body covering the outer ends of all of said bores, said body and said cover member being so relatively formed as to provide a space communicating with the outer ends of said bores; a propelling charge in each of said propelling charge chambers; projectiles in said bores adapted to be driven rearwardly so as to compress the contents of said propelling charge chambers; and means for communicating an explosive blast through said space into the outer ends of said bores to drive said projectiles rearwardly, whereby the contents of said propelling charge chambers will be compressed and said propelling charges ignited to discharge said projectiles from said bores and through said shell.

7. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a shell around said body, said body and said shell being so relatively formed as to provide a space between them communicating with the outer ends of all of said bores; sealing means between the upper and lower ends of said body and said shell, whereby the interior of said shell will be protected against hydrostatic well pressure; a propelling charge in each of said propelling charge chambers; projectiles in said bores adapted to be driven rearwardly so as to compress the contents of said propelling charge chambers; and means for communicating an explosive blast through said space into the outer ends of said bores to drive said projectiles rearwardly, whereby the contents of said propelling charge chambers will be compressed and said propelling charges ignited to discharge said projectiles from said bores and through said shell.

8. In a perforating gun of the character described, wherein a propelling charge is fired by driving the projectile rearwardly so as to compress the propelling charge, the combination of: a gun body having a plurality of gun bores leading thereinto from the face thereof, there being a propelling charge chamber communicating with the rear end of each bore; a shell around said body, said body and said shell being so relatively formed as to provide a space between them communicating with the outer ends of all of said bores; seal-

ing means between the upper and lower ends of said body and said shell, whereby the interior of said shell will be protected against hydrostatic well pressure; a propelling charge in each of said propelling charge chambers; projectiles in said bores adapted to be driven rearwardly so as to compress the contents of said propelling charge chambers; and means for communicating an explosive blast through said space into the outer ends of said bores to drive said projectiles rearwardly, whereby the contents of said propelling charge chambers will be compressed and said propelling charges ignited to discharge said projectiles from said bores and through said shell, said last named means comprising walls forming a firing charge chamber communicating with said space, a firing charge in said firing charge chamber, and means for exploding said firing charge.

9. The method of firing a perforating gun structure having a gun body with loaded gun bores, a sleeve on said gun body to cover said bores, and a space within said sleeve communicating with said bores, comprising the steps of producing a pressure in the gun structure, and conducting said pressure through said space to said gun bores to cause firing of the loads therein.

10. The method of firing a perforating gun structure having a gun body with loaded gun bores, a sleeve on said gun body to cover said bores and seal the same against external pressure, and a channel communicating with all of said bores, comprising the steps of producing a pressure in the gun structure, and conducting said pressure through said channel to said gun bores to cause firing of the loads therein.

11. A perforating gun comprising a gun body having loaded gun bores, a sleeve on said body to cover the outer ends of said bores and seal the same against external pressure, means operable to produce a pressure, means for conducting said pressure to said gun bores, and means acting in response to said pressure to fire said loads.

12. In a perforating gun of the character described, the combination of: a gun body having a plurality of gun bores opening at their outer ends in the face thereof; a shell surrounding said body in sealed relation thereto; projectiles in said bores having associated pressure activated charges for propelling them from said bores; and means for subjecting said charges to an activating pressure, including a channel interconnecting the outer ends of said bores, one side of said channel being formed by the body and the other side thereof being formed by the shell.
